UNITED STATES PATENT OFFICE.

LINZY BROOKS, OF RAINIER, OREGON

TRAFFIC-SIGNAL.

1,381,398.

Specification of Letters Patent. Patented June 14, 1921.

Application filed February 28, 1920. Serial No. 361,976.

To all whom it may concern:

Be it known that I, LINZY BROOKS, a citizen of the United States, residing at Rainier, in the county of Columbia and State of Oregon, have invented new and useful Improvements in Traffic-Signals, of which the following is a specification.

This invention relates to directional signals for automobiles and other vehicles and 10 the principal object of the invention is to provide means for indicating when the vehicle is to be turned to the right, the left or is to be stopped.

Another object of the invention is to provide means for ringing an alarm when the signal is given to call the attention of pedestrians or other cars to the signal.

This invention also consists in certain other features of construction and in the 20 combination and arrangement of the several parts, to be hereinafter fully described, illustrated in the accompanying drawings and specifically pointed out in the appended claim.

25 In describing my invention in detail, reference will be had to the accompanying drawings wherein like characters denote like or corresponding parts throughout the several views, and in which:—

30 Figure 1 is a view showing the device in use on an automobile.

Fig. 2 is an enlarged view of the casing and its attached parts.

Fig. 3 is a sectional detail through said 35 casing.

Fig. 4 is an enlarged view of the operating means which are adapted to be fastened to the steering column.

Fig. 5 is a detail view showing the electrical connection.

Fig. 6 is a longitudinal sectional view of the semaphore casing.

In these views 1 indicates the casing for containing the semaphore arms 2, these arms 45 being pivoted in the casing at its upper end by the pin 3. As shown the outer edge of the casing is open to permit the arms to swing outwardly and the shape of the casing is such that when the arms are in inoperative 50 position they will be entirely inclosed by the casing and cannot be seen from either the front or rear. An arm 4 is connected with the upper part of the casing and this arm carries the clamping means 5 for engaging 55 with a part of the wind shield frame to hold the casing in position. Each of the sema-

phore arms is provided with an annular extension 6 at its upper end which extends beyond the pivotal point and the operating wire 7 is connected to each extension. These 60 wires pass through the covering tubes 8 to the actuating mechanism 9 on the steering post of the automobile. This mechanism consists of a case 10 provided with the longitudinally extending guideways 11. These 65 guideways receive the longitudinally movable members 12 which have their upper ends connected with the wire 7. These members are provided with the handles 13 by which they may be manually moved. 70 The tubes 8 have their ends secured to the outer end of the case 10. A clamp 14 holds the case 10 to the steering column. I provide three semaphore arms, one of which contains the word "Right," another the 75 word "Left," and the third the word "Stop" and the operating members 12 are made of different lengths so that they have different lengths of strokes. In this way one of the arms will be moved outwardly to extend 80 at right angles to the case, another arm will be moved outwardly to extend at an acute angle from the case and the third will be moved to extend at an obtuse angle from the case.

I provide an electrically operated alarm 15 on the case which is in electrical connection with any suitable form of battery and a switch 16 is located in said circuit. This switch is carried by the case 10 and consists of a stationary plate 17 connected with the inner end of said case and a spring plate 18 which normally projects across the path of the actuating members 12, said plate being so arranged that when the members are moved 95 to actuate the semaphore arms they will strike the spring plate and force it into contact with the other plate and thus complete the circuit and cause the alarm to sound. The alarm will continue to sound until the 100 actuating member is returned to its normal position and the semaphore arm lowered. Thus the attention of the pedestrians and drivers of other cars will be called to the 105 semaphore arms so that they will readily see that the car is to make a turn or is going to stop.

A bracket 4' is carried by the arm 4 and this bracket supports the outer ends of the tubes 8 and also supports the conductors 119 leading to the alarm 15.

It is thought from the foregoing descrip-

tion that the advantages and novel features of my invention will be readily apparent.

I desire it to be understood that I may make changes in the construction and in the combination and arrangement of the several parts, provided that such changes fall within the scope of the appended claim.

What I claim is:—

An automobile signal comprising a signal box, a relatively long arm having its outer end connected to the box, clamping means

on the other end of the arm for engaging the windshield frame, a bracket on said arm, signal arms in the box, actuating means located adjacent the driver's seat, flexible members leading from the actuating means to the signal arms and tubes for said means having their outer ends supported by said bracket.

In testimony whereof I affix my signature. 20

LINZY BROOKS
